CARTON HAVING A HINGED RECLOSEABLE TOP
Francis A. Chidsey, Jr., Devon, Pa., assignor to Container Corporation of America, Chicago, Ill., a corporation of Delaware

Filed July 26, 1965, Ser. No. 474,687

6 Claims. (Cl. 229—51)

This invention relates to a hinged top carton having means to provide for opening and reclosing of the carton, and in particular, to an improved construction of such type carton.

Commonly, cartons formed of foldable paperboard can be opened at a hinged top panel separable from the side and front walls of the underlying tray. When good reclosing of carton is desired, a hood can be formed with the top panel by having interconnected side panels hinged to its side and front edges for overlapping the adjacent walls of the tray. In carton of this general type, it is desirable to secure the free edges of the panels to eliminate the possibility of accidental opening the carton or marring its appearance. A typical problem area is in securing the side panels of the hood to the tray since they must be separated from the tray body upon opening the hood.

This invention relates to an improved side panel construction including opposite end sections having free edge portions spaced further from the hinged connection of the side panel to the top panel than the free edge of a recessed intermediate section of the panel. Thus, the side panel of the hood are fixedly secured at its opposite ends to the tray body therebeneath while the intermediate section is recessed from the edge of the carton. This side panel construction is particularly suited for continuous inline fabrication on a conventional gluing machines which can be located relative to the hinged connection of the hood side panel between the lower free edges of the end and intermediate sections operable to apply adhesive to the enlarged end sections only. Thus, although the gluer is not retracted, since none of said intermediate section extends past the gluing machine adhesive is not applied to the intermediate section of the hood side panel but is applied only to the end section.

Accordingly, an object of this invention is to provide in a carton formed from a blank of foldable paperboard and having a hood adapted to being opened and closed, an improved hood side panel construction having enlarged end sections suitable to being bonded at locations spaced further from the hinged connection of the side panel than the free edge of the intermediate section of the panel.

Another object of this invention is to provide an im-
ment method of forming a carton of the type described in the previous object, which method includes applying an adhesive with a straight in-line gluer to the end sections of the hood side panel at the portion of the side panel spaced beyond the free edge of the intermediate section thereof.

These and other objects will be more fully appreciated after reviewing the following specification including the accompanying single sheet of drawing, wherein:

FIG. 1 is a perspective view of a carton having an embodiment of the subject improved hood side panel construction and showing therein the manner in which the hood side panel can have adhesive applied thereto;

FIG. 2 is a top plan view of a blank suitably cut and scored to form the carton disclosed in FIG. 1;

FIG. 3 is an end elevational view of the carton disclosed herein shown with the hooded top in the open position relative to the carton body.

In the drawing, a carton 10 is shown in which the improved hood side panel construction is incorporated. The

2

carton includes basically a tray section 12 and a hood section 14 hinged thereto and adapted to provide for opening and reclosing the carton. In the closed position of the carton, the side walls of the tray and hood sections telescope over one another.

A blank 16 suitably cut and scored for forming the carton disclosed herein is shown in plan view in FIG. 2. The blank includes successive main panels 20, 22, 24, 26 and 28 hingedly interconnected to one another along parallel score lines 21, 23, 25 and 27. The panels are folded to a tubular structure open at its ends with the panels 20 and 28 overlapping one another in face to face relation and being bonded together as at 30. The tubular structure has a closure panels for maintaining the main panels squared and further for closing the sides of the carton. The closure panels include full height inner side wall panels 44 hinged along scores 45 to the side edges of bottom panel 26; outer side wall panels 46 hinged along scores 47 to the side edges of top wall 22; and tuck in flaps 50 and 52 hinged along scores 51 and 53 to the side edges of the rear and front panels, respectively.

It is noted that the free or remote edge at the intermediate section of each outer side wall panel 46 is cut away or recessed as at 55 to provide enlarged end sections 56 and 58 which extend from score 47 approximately the full height of the carton. The carton is formed initially to the tubular structure, as was previously described, and loaded with the product through the open end. Thereafter, the inner side wall panels 44 are folded normal to the bottom wall to close the open ends of the tubular section and the tuck in flaps 50 and 52 folded normal to the respective rear and inner front wall against the positioned under side wall panels 44. This folding of the panels 44 and flaps can be accomplished by plows or like devices (not shown) in the well known manner, as the carton is conveyed in a direction indicated by the arrow 60 generally parallel to score lines 45, 47, 51 and 53.

As the carton is conveyed in the direction of the arrow 60, a conventional inline gluer, represented in FIG. 1 by wheel 62 rotatable about axis 64 is spaced from the hinged scores 47 so that it engages only the enlarged end sections 56 and 58 of the panel. In this manner, the gluer applies adhesive to the passing carton as continuous strips 66 and 68 only on the end sections 56 and 58. These glue strips are thus on the outer side wall panels between the free edge 70 of the intermediate recessed section 55 and the free edges 71 of the end sections. The outer side wall panel 46 is thereafter folded or plowed over to engage the tray side wall structure therebeneath.

Preferably, the end sections 56 and 58 of each outer side wall panel are proportioned relative to the tuck in flaps 50 and 52 disposed therebeneath to cover the flaps. Thus, by bonding each front end section 58 to front tuck in flaps 52, a rigid hood is formed between the outer side wall panels 46, the tuck in flap 52, and the inner front wall panel 20. The hood, once broken from the lower tray of the carton, can be pivoted as a unit about the rear edge of the top panel. Similarly, the enlarged rear end sections 56 can cover rear tuck in flaps 50 and be adhesively bonded thereto, and further can extend past the flaps and be bonded to the portions of the inner side wall panels 44 exposed forwardly of the rear tuck in flaps. This secures the outer side wall panel to the inner side wall panel for maintaining the carton closed.

Since the hood 14 in the carton disclosed hinges about the top wall hinge formed at the juncture 23 of rear wall 24 and the top wall, in order to open the hood the hood side panels 46 must be separated from the tray side walls 44. To accommodate this, the hood side wall panels 46 have provided therein a weakened section 73 extending

from the free edge 70 of the intermediate recessed section 55 to the hinged score 23 for the top wall panel and hood. The weakened line thus fails upon lifting the hood from the tray to permit the carton to be opened.

The subject carton can be opened by a readily separable connection between the tray and hood in the form of a tear strip 82 defined by general parallel weakened cut lines 84 and 85 between glue panel 38 and reclosure panel 80. The glue panel 38 is adhesively bonded to the front panel 20 and forms the only connection between the telescoping front panels of the tray and hood. Thus, upon removing tear strip 82 from the carton, reclosure panel 80 is completely free from connection to the hood.

A locking tab 86 can be formed in the reclosure panel 80 for engagement with the front hood panel. The tab 86 is formed in the panel 80 by an upwardly extending bell shaped cut 87 which tab is adapted to cooperate with an upwardly shaped cut 89 formed in the hood front panel 20. The lock can be engaged upon reclosing the carton by telescoping the hood over the tray and by folding the reclosure panel forwardly until engaged with the hood front wall, and thereafter fitting the locking tab 86 through the receiving cut 89 in the hood front panel.

While various constructions shown in the subject carton, other modifications can be made without departing from the inventive concept disclosed herein. For example, the ready separable means between the hood and tray can be formed on a wall other than the front wall of the tray, such as by providing a tear strip and glued flap connection on the hood top wall or tray bottom wall. In such a case, the front wall of the carton still would comprise telescoping inner and outer panels formed from the tray and the hood. Also, by extending the rear tuck in flap 50 forwardly of the carton and by shaping the rear end sections 56 to complement the tuck in flap for bonding the end section only to the tuck in flap, the entire hood could pivot about the hinged connection 25 between the rear wall and the bottom wall. Similarly, the top panel can have provided therein a score (not shown) extending between the scores 21 and 23 to provide that only the forward portion of the top panel opens. In such a case, the rear end section can be extended forwardly to beyond the top hinge, and weakened lines can be formed in the hood side panels to extend from the free edge of the recess to the hood top hinge line. Accordingly, it is desired that invention be limited only by the scope of the claims herein after following.

I claim:

1. A carton formed of foldable paperboard, comprising:

- (a) opposed top and bottom walls, and opposed pairs of side walls and front and rear walls extended between and hingedly connected to corresponding side, front and rear edges of the top and bottom walls;
- (b) the side walls and the front wall including overlapping inner and outer panels hinged to the top and bottom walls;
- (c) front and rear end flaps hinged to the front wall inner panel and to the rear wall and extended between the side wall inner and outer panels;
- (d) each of said side wall outer panels being hinged at its upper edge to a related side edge of the top wall and extending therefrom toward the bottom wall, and presenting remote end sections that overlap and completely cover the related end flap and presenting an intermediate section having a lower free edge spaced above the lower free edges of said end sections to provide a gap in the side wall outer panel between the end flaps;
- (e) said end sections having horizontal strips of adhesive applied to the underside thereof, at locations vertically between the lower free edges of the end and intermediate sections operable to secure said side wall outer panel to the opposite end flaps and

75

to the portion of the side wall inner panel exposed forwardly of the rear end flap for defining a top hood and for maintaining the side wall outer panel down relative to the side wall inner panel;

- (f) readily separable means for maintaining the front wall inner and outer panels in overlapped relation;
- (g) the side wall outer panel having a weakened section inclined upwardly and rearwardly from the lower free edge of the intermediate section at the rearward end thereof to a hinge line of the top wall extending parallel to the front and rear walls;
- (h) the top wall and hood being operable thereby upon separation of the front wall inner and outer panels and the breaking of the side wall outer panel weakened section to pivot about the top hinge line for opening and closing the carton.

2. A carton according to claim 1, wherein the top hinge line is at the juncture of the rear wall and the top wall, and the rear end section extends forwardly of the rear wall to completely cover the rear end flap and further to cover a rearward portion of the side wall inner panel forwardly of the rear end flap.

3. A carton formed of foldable paperboard, comprising:

- (a) opposed top and bottom walls, and opposed pairs of side walls and front and rear walls extended between and hingedly connected to corresponding side, front and rear edges of the top and bottom walls;
- (b) the side walls and the front wall including overlapping inner and outer panels hinged to the top and bottom walls;
- (c) front end flaps hinged to the front wall inner panel and extended between the side wall inner and outer panels;
- (d) each of said side wall outer panels being hinged at its upper edge to a related side edge of the top wall and extending therefrom toward the bottom wall, and presenting enlarged front and rear end sections and an intermediate section having a lower free edge spaced above the lower free edges of said end sections to provide a gap in the side wall outer panel between the end flaps, the front end section overlapping and completely covering the front end flap;
- (e) said end sections having horizontal strips of adhesive applied to the underside thereof, at locations vertically between the lower free edges of the end sections and said intermediate section operable to secure the end sections to the front end flap and to the side wall inner panel for defining a hood and for maintaining the side wall outer panel down relative to the side wall inner panel;
- (f) readily separable means for maintaining the front wall inner and outer panels in overlapped relation;
- (g) the side wall outer panel having a weakened section extending between the lower free edge of the intermediate section and a hinge line of the top wall extending parallel to the front and rear walls;
- (h) the top wall and hood being operable upon separation of the front wall inner and outer panels and breaking the weakened section to pivot about the top hinge line for opening and closing the carton.

4. A carton formed of foldable paperboard, comprising:

- (a) opposed top and bottom, side, and front and rear walls hingedly connected together;
- (b) the side walls including overlapping inner and outer panels hinged to the top and bottom walls;
- (c) front end flaps hinged to the front wall and extended between the side wall inner and outer panels;
- (d) each of said side wall outer panels being hinged at its upper edge to a related side edge of the top wall and presenting enlarged end sections and an intermediate section having a lower free edge spaced above the lower free edges of said end sections to

- provide a gap in the side wall outer panel, and the front end sections completely covering the front flaps;
- (e) said end sections having adhesive applied to the underside thereof, between the lower free edges of the end and intermediate sections operable to secure said side wall outer panel to the front end flap and to the side wall inner panel for defining a hood and for maintaining the side wall outer panel down relative to the side wall inner panel;
- (f) the side wall outer panel having a weakened section extending between the lower free edge of the intermediate section and a hinge line of the top wall extending parallel to the front and rear walls;
- (g) the hood being operable upon breaking the weakened section to pivot about the top hinge line for opening and closing the carton.
5. A carton formed of foldable paperboard, comprising:
- (a) opposed top and bottom walls, and opposed pairs of side walls and front and rear walls extended between and hingedly connected to corresponding side, front and rear edges of the top and bottom walls;
- (b) the side walls and the front wall including overlapping inner and outer panels hinged to the top and bottom walls;
- (c) front and rear end flaps hinged to the front wall inner panel and to the rear wall and extended between the side wall inner and outer panels;
- (d) each of said side wall outer panels being hinged at its upper edge to a related side edge of the top wall and presenting remote end sections that overlap and cover the related end flap and presenting an intermediate section having a lower free edge spaced above the lower free edges of said end sections to provide a gap in the side wall outer panel between the end flaps;
- (e) said end sections having horizontal strips of adhesive applied to the underside thereof, at locations vertically between the lower free edges of the end sections and said intermediate section operable to

10

5

25

- secure said side wall outer panel to the opposite end flaps for defining a hood;
- (f) readily separable means for maintaining the front wall inner and outer panels in overlapped relation to hold the hood closed relative to the carton.
6. A carton formed of foldable paperboard, comprising:
- (a) major top and bottom walls, and opposed pairs of side walls and front and rear walls extended between and hingedly connected to corresponding side, front and rear edges of the top and bottom walls;
- (b) the side walls and the front wall including overlapping inner and outer panels hinged to the major walls;
- (c) each of said side wall outer panels extending from its hinged connection to one major wall toward the other major wall, and presenting remote end sections and an intermediate section having a free edge spaced between the free edges of said end section to provide a free edge gap in the side wall outer panel;
- (d) said end sections having strips of adhesive applied to the underside thereof, at locations between the free edges of the end and intermediate section operable to maintain the side wall outer panel down relative to the side wall inner panel;
- (e) readily separable means for maintaining the front wall inner and outer panels in overlapped relation;
- (f) said side wall outer panel having a weakened section extended thereacross from the free edge of the intermediate section operable to break upon opening the carton.
